UNITED STATES PATENT OFFICE.

EDWIN E. CARLSON AND LAWRENCE A. STEAD, OF CHESTER, PENNSYLVANIA.

METHOD OF DYEING WARPS.

Application filed July 15, 1926. Serial No. 122,525.

This invention relates to method of dyeing yarn in groups, commonly known as warps.

Warps, as usually dyed, are passed around rollers and through the dye bath of a dyeing machine. As the warp is dyed the dye bath is gradually exhausted of its coloring matter and becomes a lighter shade. The result is that the warp is dyed a non-uniform shade, the color at one end of the warp being of the proper shade and gradually becoming lighter toward the other end of the warp which is of a noticeably lighter shade. The yarn of this warp, when worked into a fabric, produces streaks which have been the cause of many second grade products.

The object of our invention is to provide a method whereby warps of practically any length may be quickly dyed a uniform shade.

This object, and other advantageous ends which will be described hereinafter, we attain in the following manner, reference being had to the accompanying drawings in which

Figure 1 is a schematic plan view of apparatus for carrying our method into effect, Figure 2 a front elevation of the apparatus shown in Figure 1, some of the parts being omitted,

Figure 3 an end view of the apparatus looking from the right of Figure 2, and showing the parts omitted in Figure 2,

Figure 4 a central section through a reel which may be used for carrying our method into effect, illustrating how the warp is wound thereon.

Referring to the drawings, the apparatus includes a vat 1 for containing a dye bath, a reel 2 which is removably mounted for rotation on the edges of the vat, a frame 3 for removably supporting the reel when winding a warp thereon for dyeing, a frame 4 for removably supporting the reel when unwinding the dyed warp therefrom, and hoisting mechanism 5 for raising, conveying and lowering the reel from and to vat 1, frame 3 and frame 4.

The reel may be of the type disclosed in our application filed under even date, which has trunnions 6 rotatable in bearing blocks 7 adapted to rest in recesses 8 in vat 1, frame 3 and frame 4. The warp wound on the reel is wound on spaced bars 9 removably mounted in grooves 10 in bar supports 11 mounted on flanges 12 of the reel. The reel may be rotated by suitable driving mechanism 13 operatively connected with vat 1, frame 3 and frame 4 respectively.

The hoisting mechanism includes a lifter 14 and a track 15 on which the lifter travels. The lifter is connected for raising the reel by attaching each pair of hooks 16 to the extending end of each bearing block 7 on the ends of the reel.

The warp to be dyed is brought to the frame 3 in trucks or other receptacles 17 and is passed over a guide roll 18 to the reel.

The dyed warp, when unwound from the reel, passes between a pair of rolls 19 which squeeze the dye liquid out of the wet warp, into a receptacle 20 and then passes over a series of guide rolls 21 and through suitable folding mechanism 22 which folds the warp as it fills receptacle 23.

In dyeing, the warp is first wound on a reel by passing it over guide roll 18 and tying or otherwise fastening the end to one of the bars 9 on the reel. The warp is then wound in spaced layers on the bars as shown in Figure 4 and as described in our co-pending application mentioned above. It is to be understood that other types of reels may be used and the warp may be wound on the reel in any desired manner, so long as the warp is applied to a reel. After the warp is wound, the hoisting mechanism is connected for raising reel 2 from frame 3 and lowering it into vat 1, as indicated by the arrows in Figure 2. The reel is then rotated by driving mechanism 13 until the warp is dyed.

As the reel is rotated, the warp wound thereon will churn the dye liquor and thus keep it thoroughly mixed and of uniform shade throughout. The dye bath at the end of the dyeing period will be exhausted of some of its coloring matter and will be of a lighter shade. The lighter shade dye having the same effect on the entire warp, will dye the entire warp a uniform shade.

After dyeing, the hoisting mechanism is connected for raising the reel from the vat and lowering it onto frame 4 for unwinding the warp as indicated by the arrows in Figure 2.

In unwinding, the end of the warp is passed between rolls 19 which squeeze out the dye liquid from the wet warp into receptacle 20 and then passed over guide rolls 21 and down through the folding mechanism 22 into receptacle 23. The reel is then rotated and bars 9 removed as the spaced layers of warp are unwound from the reel. The empty reel is then conveyed by the

hoisting mechanism from frame 4 to frame 3, as indicated by the arrows in Figure 2, where another warp may be wound thereon.

It may, in some cases, be desirable to wind and unwind the warp onto and from the reel at the frame 3 and use frame 4 merely as a support for the reel prior to hoisting and placing it in the vat to dye the warp. When this is desirable, the reel after dyeing is removed from the vat and placed on frame 3 where the dyed warp is first unwound and then another warp wound on the reel. The reel after having the warp wound thereon is conveyed by the hoisting mechanism to the opposite side of the vat and placed in frame 4 to be ready for dyeing after the reel, in the vat is removed therefrom.

It is thus seen that dyeing warp by this method permits the reels to be conveyed to and from the vat for winding and unwinding the warps, to suit different requirements. From actual use, we have found that warps may be quickly and uniformly dyed by unwinding a dyed warp from one reel and winding a fresh warp on a second reel, while a warp on the third reel is being dyed in the vat, thereby avoiding delays in waiting to perform one operation while another operation is being performed.

While we have described our invention with a particular apparatus, it will be understood that the various parts may be changed without departing from the spirit thereof, and hence we do not limit ourselves to the precise construction set forth, but consider that we are at liberty to make

such changes and alterations as fairly come within the scope of the appended claims.

Having thus described our invention, what we claim as new and desire to secure by Letters Patent is:—

1. A method of dyeing warps consisting in applying the material to be dyed on a reel in spaced layers, immersing the reel in a dye bath, rotating the reel until the material is dyed, removing the reel from the dye bath, and removing the warp from the reel.

2. A method of dyeing warps consisting in applying the material to be dyed on a reel in spaced concentric layers, immersing the reel in a dye bath, rotating the reel until the material is dyed, removing the reel from the dye bath, and removing the warp from the reel.

3. A method of dyeing warps consisting in winding the material to be dyed on a reel in spaced concentric layers, immersing the reel in a dye bath, rotating the reel until the material is dyed, removing the reel from the dye bath, and unwinding the warp from the reel.

4. A method of dyeing warps consisting in winding the material to be dyed on a reel, immersing the reel in a dye bath, rotating the reel until the material is dyed, removing the reel from the dye bath, unwinding the warp from the reel, and conveying the unwound reel to a position for winding another warp thereon.

In testimony whereof we have signed our names to this specification.

EDWIN E. CARLSON.
LAWRENCE A. STEAD.
